(57) **CLAIM**

The ornamental design for a cover for lens of portable electronic apparatus, as shown and described.

DESCRIPTION

FIG. 1 is a front perspective view of a cover for lens of portable electronic apparatus showing my new design; FIG. 2 is a rear perspective view thereof; FIG. 3 is a bottom perspective view thereof; FIG. 4 is a front view thereof; FIG. 5 is a rear view thereof; FIG. 6 is a left side view thereof; FIG. 7 is a right side view thereof; FIG. 8 is a top view thereof; FIG. 9 is a bottom view thereof;

FIG. 10 is a top front perspective view thereof showing a detached state in use; and, FIG. 11 is a top front perspective view thereof showing an assembled state in use.

The broken lines depict portions of the cover for lens of portable electronic apparatus that form no part of the claimed design.
